UNITED STATES PATENT OFFICE.

OLIVER E. BARTHEL, OF DETROIT, MICHIGAN.

INTERNAL-COMBUSTION ENGINE.

1,289,606.

Specification of Letters Patent. Patented Dec. 31, 1918.

Application filed October 17, 1914. Serial No. 867,074.

To all whom it may concern:

Be it known that I, OLIVER E. BARTHEL, a citizen of the United States of America, residing at Detroit, in the county of Wayne, 5 and State of Michigan, have invented certain new and useful Improvements in Internal-Combustion Engines, of which the following is a specification, reference being had therein to the accompanying drawings.

10 This invention relates to improvements in internal combustion engines, and its object is, in an engine having a mechanically operated overhead valve to provide an arrangement of operating mechanism for the 15 valve which will afford efficient lubrication of the parts and prevent noise of operation. A further object of the invention is to provide an arrangement of inlet passages which will effect an even distribution of combustible charges to the several inlet valves at 20 all times, and to provide other new and useful features in the construction whereby ready access may be had to the crank shaft bearing and the work of replacement and 25 repair is facilitated.

With these and other ends in view the invention consists in the matters hereinafter set forth and more particularly pointed out in the appended claims, reference being had 30 to the accompanying drawings in which--

Figure 1 is a side elevation of an engine embodying the invention, and showing parts broken away to disclose the internal construction;

35 Fig. 2 is an end elevation of the same; Fig. 3 is an enlarged side elevation of the upper end of the cylinders, the head therefor and the cam shaft chamber, with parts broken away and in section to disclose the 40 internal construction;

Fig. 4 is a plan view of Fig. 3 with parts broken away and in section to disclose the internal construction;

Fig. 5 is a transverse section of the head 45 and cam chamber substantially upon the line V—V of Figs. 7 and 4;

Fig. 6 is a like section upon line VI—VI of Figs. 4 and 7;

Fig. 7 is a horizontal section through the 50 head substantially on the line VII—VII of Fig. 5; and

Fig. 8 is a sectional detail of a portion of a tappet.

For convenience of illustration a four 55 cylinder engine is shown in the drawing, but it will be understood that engines hav-

ing any desired number of cylinders may be constructed with the invention embodied therein, and other changes in the form or arrangement of parts may be made without departing from the spirit of the invention. I do not, therefore, limit myself to the form or arrangement shown.

As shown in the drawings, the cylinders 1 are cast integral with the upper half 2 of a crank case, said half of the crank case being provided with suitable bearings 3 for a crank shaft 4. The lower half 5 of the crank case is arranged to be bolted to the flange on the upper half of the case and at 70 its rear end is formed to engage a bearing member 6 forming the lower half of the rear bearing for the crank shaft. At its rear end, the upper half 2 of the crank case is formed with a semi-circular seat or flange 75 7 around the bearing 3 for a fly wheel casing 8, and the half bearing 6 is formed with a semi-circular flange 9 forming a continuation of the seat 7 and to which the casing 8 is detachably secured by means of 80 bolts 10.

By forming the rear crank shaft bearing with a lower detachable half which is separate from the lower half of the crank case, and providing this half bearing with the 85 flange 9, the fly wheel casing is attached to the engine independently of the lower half of the crank case and each may be detached without removing the other. Access may therefore be had to the crank shaft to adjust or renew the bearings without disconnecting the fly wheel casing or the usual transmission casing which is attached thereto but not shown in the drawings. With 90 this construction it is not necessary to dismount the whole engine in order to get at the crank shaft or the fly wheel and its adjacent parts.

The upper end of the casting forming the several cylinders is faced off to receive a 100 head 11 which is faced to seat thereon and is bolted thereto in the usual manner. This head is formed with seats over the upper end of each cylinder for an inlet valve 12 and an exhaust valve 13. The casting 105 forming the cylinder is formed intermediate the two pairs of cylinders with a passage 14 opening through the side of the casting, and over the open end of the passage, a pipe leading from a carburetor or other source 110 of combustible charges, not shown, is adapted to be secured. The upper end of

the passage opens through the top of the casting and into the passage or chamber 15 formed in the lower part of the head. All of the inlet ports for the several cylinders 5 which are controlled by the valves 12, open into this passage or chamber 15 and an exhaust passage 16 for the exhaust ports of the two adjacent center cylinders, extends upward through the chamber 15 at the center 10 thereof and opens through the side of the head intermediate its ends. The exhaust ports for the two end cylinders open into passages 17 which also open through the side of the head so that an exhaust 15 manifold, not shown, may be secured to the side of the head to receive the exhaust from the several exhaust passages.

As the inlet ports all open from a common inlet passage which is supplied with 20 combustible vapor intermediate its ends from the carburetor, and as said chamber 15 surrounding the center exhaust passage forms an annular passage, the combustible fluid circulates freely and continuously 25 therein materially aiding by the inertia of its flow, its entrance into the cylinders and preventing partial condensation or variation in richness of the charges, due in other forms of inlet passages or manifolds, to the 30 retardation or banking of the vapor in the ends of the passage and the sudden changes in the direction of flow. The chamber from which all of the inlets open also serves by reason of the volume of gas therein, to dis- 35 sipate the pulsations in the flow caused by the opening and closing of the valves and gives a substantially constant suction in the carburetor.

All of the space within the head not taken 40 up by the inlet and exhaust passages is chambered to receive water, and these several water chambers 18 are in communication with the water jacket of the cylinders in the usual manner, a suitable pump 19 shown in Fig. 1 being provided to maintain 45 a circulation of water through the cylinder jacket, chambers in the head and through a suitable cooler or radiator not shown. The explosive charges in the several cylinders 50 are ignited by means of spark plugs 20 screwed into openings in the sides of the cylinders adjacent to the head 11.

The several inlet and exhaust valves are provided with stems 21 which extend vertically upward through suitable bearings in the head 11, and adjustably secured to the upper ends of these stems, are yokes 22, the lower guide shanks 23 of each of which are bored and internally screw threaded to receive the stems of the valves, and a lock nut 24 on each stem engages the lower end of the shank to lock the stem in the position to which it is adjusted in the bore. These shanks 23 of the several yokes, are guided in 65 suitable guide bearings in the bottom of a

suitable casing adapted to contain the several yokes, said casing being preferably of oval shape in cross section and formed in two parts, the lower half 25 being preferably cast integral with the head 11 and supported by and spaced therefrom by means of brackets or webs 26. The two halves of the chamber or casing are flanged and bolted together and the upper half is formed with suitable guide bearings for the upper 70 rounded ends or shanks 27 of the yokes.

The several inlet and exhaust valves are operated in timed relation to the movement of the pistons in the cylinders, by means of a cam shaft 28 which is provided with cams 29, and is mounted in suitable bearings on the lower half 25 of the cam shaft casing or chamber. The yokes 22 span the shaft and are provided with suitable rolls 30 and 31 to engage the cams which thus act to positively move the yoke in both directions and open and close the valves. Each of the rolls 31 is carried by a sliding member 32 engaging a bore in the upper end of the yoke, and a spring 33 interposed between the sliding member and the inner end of the bore normally holds the roll 31 in contact with the cam 29 which is formed with a separate cam surface for each roll of each pair. To prevent the member 32 from turning within its bore, it is provided with a pin 34 engaging a slot 35.

The cam shaft 28 is rotated in timed relation to the rotation of the crank shaft of the engine, by means of a shaft 36 and gears 37 indicated in dotted lines in Fig. 2 for transmitting motion from the crank shaft to said shaft 36, similar gears 38 being provided at the upper end of the shaft 36 to transmit motion therefrom to the cam shaft, 105 these last named gears being contained within the ends of the casing for the cam shaft.

This cam shaft casing or chamber is adapted to contain oil which is supplied thereto from a pump 39 shown in Fig. 1 110 and located in the bottom of the engine crank case. From the pump, oil is conducted by a pipe 40 to the cam shaft chamber, and this pump also supplies oil to the other parts of the engine, such as the cups 115 41 into which the cranks dip, a pipe 42 connecting the pump with these cups. From the cam shaft chamber the oil overflows 43 into the upper part of the crank case, and thus a level of oil is 120 maintained at all times in the cam shaft chamber to thoroughly lubricate the cams and rolls, and also to deaden the noise of contact of the cams with the rolls.

A suitable packing 44, shown in Figs. 3 125 and 5, is provided for each of the shanks 23 of the yoke to prevent leakage of oil from the casing around these shanks. Lugs 45 on the side of the casing 25 engage each side of each yoke and prevent the yokes from 130

turning within the casing. Each yoke is thus accurately guided in its up and down movement and is held in perfect alignment with the stem of the valve by the guide bearings in the upper and lower parts of the cam shaft casing.

By spacing the cam shaft casing from the head 11, the valve stems are made accessible for adjustment and are cooled by exposure to the air, and the cam shaft is located within a chamber by itself where it will not be affected by heat from the cylinders. Wear and consequent noise is thereby prevented, and an accurate opening and closing of each valve is insured by the yoke upon which the cam operates.

Having thus fully described my invention what I claim is:

1. In an internal combustion engine, the combination of a plurality of cylinders having a head portion formed with a chamber provided with ports opening directly into the upper ends of all of said cylinders, said chamber extending from side to side of said head portion and having an inlet opening midway of its length, valves for said ports, and means for supplying combustible fluid to said chamber through said inlet opening.

2. In an internal combustion engine, the combination of a series of cylinders, a head portion extending across the upper ends of all of said cylinders and formed with a supply chamber having ports opening directly into the upper ends of all of said cylinders, said chamber being continuous from one end cylinder of the series to the other end cylinder and extending from side to side of the head portion with an inlet opening near one side intermediate its ends, valves controlling the several ports, and means for supplying combustible fuel to said chamber through said inlet opening.

3. In an internal combustion engine, the combination of a plurality of cylinders having inlet and exhaust ports and a chamber into which all of said inlet ports directly open, an exhaust passage being provided for certain of said exhaust ports which passage extends across said chamber and is surrounded thereby to permit a free circulation of combustible fluid in said chamber around said passage to all of said inlet ports, valves for closing the ports, and means for supplying combustible fluid to said chamber.

4. In an internal combustion engine, the combination of a plurality of cylinders, a head for said cylinders formed with an inlet chamber having an inlet port for each cylinder opening directly therefrom and formed with an exhaust passage extending across and surrounded by said chamber, said chamber being also provided with an inlet opening intermediate its ends opposite one side of said exhaust passage which extends across the chamber, valves for said ports, and means

for supplying combustible fluid to the inlet chamber through said inlet opening.

5. In an internal combustion engine, the combination with a cylinder, of a head for said cylinder formed with an inlet and an exhaust port, valves controlling said ports, upwardly extending stems on the valves extending through bearings in said head, a casing spaced from said head and forming a cam shaft chamber into which the valve stems extend across said space, and a cam shaft in said casing provided with cams to operate the valves.

6. In an internal combustion engine, the combination with a plurality of cylinders, of a common head for said cylinders formed with inlet and exhaust ports in the plane of the vertical axes of the several cylinders and passages leading to and from said ports, valves for said ports, stems on the valves extending through bearings in said head, a casing spaced from said head and forming a cam shaft chamber into which the valve stems extend across said space, and a cam shaft in said casing provided with cams to operate the valves.

7. In an internal combustion engine, the combination with a plurality of cylinders and pistons in the cylinders, of a common head for said cylinders formed with an inlet and an exhaust port for each cylinder in the plane of the vertical axis of said cylinder, said plane being common to all of said cylinders, valves for the ports, stems on the valves extending upwardly through the head, a casing above the head for holding oil and into which the stems extend, a cam shaft in said casing extending horizontally in the vertical plane of the cylinders and provided with cams for operating the several stems, and means for rotating the cam shaft in timed relation to the movements of the pistons.

8. In an internal combustion engine, the combination with a cylinder and a piston in said cylinder, of valves in the upper end of said cylinder having upwardly extending stems, a casing extending across the several cylinders and spaced therefrom and into which the stems extend across said space, adjusting means for each stem within the space between said cylinder and casing, and means within the casing for operating the stems in timed relation to the movement of the piston.

9. In an internal combustion engine, the combination with a cylinder and a piston in said cylinder, of valves in the upper end of said cylinder having upwardly extending stems, a cam shaft casing adapted to contain oil and into which the upper ends of the valve stems extend, a cam shaft in said casing having cams to engage the valve stems, and means in the bottom of the casing around each stem to frictionally engage the

- stem and remove the oil therefrom as the stems are reciprocated, whereby the escape of oil from the chamber around the valve stems is prevented.
- 5 10. In an internal combustion engine, the combination with a plurality of cylinders and pistons in said cylinders, of valves in the upper ends of said cylinders having upwardly extending stems, a cam shaft casing 45 extending across the several cylinders and spaced therefrom and into which the stems extend across said space, said casing being adapted to contain oil, a cam shaft in said casing having cams to engage the stems, and 50 means in the bottom of said casing surrounding each stem in frictional engagement therewith to remove the oil from the stems upon downward movement thereof, said casing being chambered around each stem to 55 receive said means.
11. In an internal combustion engine, the combination with a cylinder and a piston in said cylinder, of valves for controlling inlet and exhaust ports in the head of said cylinder, said valves having upwardly extending stems, a cam shaft casing in the vertical plane of the cylinder and provided with bearings at its upper and lower sides for 60 said valve stems, a cam shaft in said casing, 65 a yoke for each valve stem embracing the cam shaft, and cams on the cam shaft within the yokes to engage the same and operate the valve stems in both directions.
12. In an internal combustion engine, the combination with a plurality of vertically disposed cylinders and pistons in said cylinders, of a plurality of valves for controlling the inlet to and exhaust from said cylinders, said valves being positioned in the vertical 70 plane of the axes of the several cylinders, stems on the valves extending vertically
- through the upper ends of the cylinders, a cam shaft chamber extending across the upper ends of the several cylinders with the said stems projecting into said chamber, a cam shaft in said chamber provided with cams for operating the stems, and a yoke for each stem within the chamber embracing the cam shaft to be moved in two directions by the engagement therewith of said cams, said yokes being guided vertically in the upper and lower part of said chamber.
13. In an internal combustion engine, the combination with a plurality of vertically disposed cylinders and pistons in said cylinders, of a head for said cylinders provided with an inlet and an exhaust port for each cylinder and passages leading from said ports, all of the inlet ports opening directly into a common passage, valves for closing 60 said ports, valve stems for the valves extending vertically through the head, a chamber carried by the head into which the valve stems extend, a yoke on each valve stem guided in bearings in the upper and lower 65 part of the chamber, means for preventing the rotation of the yokes, a cam shaft having cams mounted in the bearings in the casing and extending longitudinally thereof, rolls on the yokes to be engaged by the cams, one of said rolls for each cam being yieldingly held in contact with said cams, and means for rotating the cam shaft in timed 70 relation to the movements of the several pistons.
- 75 In testimony whereof I affix my signature in presence of two witnesses.
- OLIVER E. BARTHEL.
